United States Patent Office.

JOSEPH WAGNER, OF NEWCASTLE, PENNSYLVANIA.

Letters Patent No. 70,764, dated November 12, 1867.

IMPROVEMENT IN WELL-TUBES.

The Schedule referred to in these Letters Patent and making part of the same.

TO ALL WHOM IT MAY CONCERN:

Be it known that I, JOSEPH WAGNER, of Newcastle, in the county of Lawrence, and State of Pennsylvania, have invented a new and useful Improvement in Deep-Well Borers and Tubes; and I do hereby declare the following to be a full and correct description of the same, sufficient to enable others skilled in the art to which my invention appertains to understand and use the same, reference being had to the accompanying drawings, which make parts of this specification, and in which—

Figures 1 and 2 are side views of my improved borer and tube, and

Figure 3 is a detached view of the point and its perforated stem.

Similar letters of reference indicate corresponding parts in the several figures.

The nature of my invention consists in the peculiar manner of attaching the point and stem to the tube, so that from the top of the tube to that part of the point where its taper begins, it shall be of even size, without any of its parts projecting.

A, in the drawings, represents the tube, and B the point, which latter is attached to a hollow stem, C, which fits into the tube A, and is provided with rows of holes corresponding to similar rows of holes in the tube A. Corresponding with the upper hole *c* in the stem C is a slot, *a*, in the tube A, a pin, *b*, passing through the slot *a* and hole *c* in such a manner that when the tube is worked toward the right, as is done in boring, the tube A will slide around the stem C until the pin *b* comes against the left corner *a'* of the slot *a*, as shown in fig. 2, whereby the holes in both the tube A and stem C are closed. It is but necessary, when the well has been bored to its desired depth, to turn the tube A to the left until the pin *b* rests against the corner *a''* of the stem C, as shown in fig. 1, when the water will be admitted, the holes in the tube A and stem C covering each other. I am aware that a patent was granted to R. F. Osgood in 1866, in which case the tube and stem are perforated and operate in a similar manner; but in his case the stem and point, cast in one piece, slide on the outside of the tube, the pin being attached to the tube, and working in a slot in the stem. In this case all the strain of the boring is on the pin in the slot, while in my tool the lower end of the tube bears equally and uniformly on the shoulder *d* of the point B, which is flush with the tube A. By my improved arrangement no shoulder is formed on the outside of the tubing, which, as in Osgood's case, would hinder the withdrawal of the tube if it becomes necessary. The point B consists of the base *e*, the angular taper *f*, and the short point proper, *g*. The advantages of constructing the point in this manner are, that the short point proper, *g*, serves to break any boulders which may be encountered in boring, while the angular taper serves as a reamer. In making the taper straight to the sharp end of the point, the latter is too much weakened, and is liable to break easily on encountering hard boulders; but by my construction this difficulty is entirely overcome.

Having thus described my invention, what I claim as new, and desire to secure by Letters Patent, is—

1. The perforated stem C of the point B encased within the tube A, in combination with the slot *a* and pin *b*, substantially as and for the purpose described.
2. The combination of the point B, constructed as described, with the perforated stem C, perforated tube A, slot *a*, and pin *b*, substantially as and for the purposes described.

The above specification of my improvement in deep-well borers and tubes signed this seventh day of May, 1867.

JOSEPH WAGNER.
